IMPULSE GENERATOR

John C. Koonz, Fort Wayne, Ind., assignor to The Magnavox Company, Fort Wayne, Ind., a corporation of Delaware

Application October 18, 1949, Serial No. 121,980

11 Claims. (Cl. 171—209)

1

The present invention relates to electrical impulse generators, designed for generating high voltage potentials of momentary duration.

It is a primary object of the invention to provide an electromagnetic generator of simple, sturdy and rugged construction, wherein the impulse is produced in response to a longitudinal sliding movement of the armature, as distinguished from a tilting, rocking or slapping motion, so that the coacting pole surfaces on the armature and field engage and disengage by smooth sliding motion rather than by the impact or hammering action commonly employed in prior art devices of this kind. The accomplishment of this object is of obvious advantage in eliminating all noise incident to operation, and is additionally important in that it avoids the wear and distortion necessarily produced by long repeated impact of the pole surfaces as they hammer against each other.

Possibly even a more important advantage of applicant's construction, however, arises from the fact that since the pole surfaces engage and disengage by sliding rather than hammering contact, they do not function as a stop or abutment limiting the movement of the armature. Instead, the movement of the armature is unrestricted and a considerable degree of overtravel may be permitted without impairing the efficiency of the generator. Thus, the armature may be positively driven by heavy, powerful and fast moving machine parts (the mechanism of a recoil operated automatic gun, for example) with assurance that the tremendous power developed by the recoil cannot damage the working parts of the generator. Obviously it follows that no unusual precautions need be taken to have the stroke of the gun parts exactly the desired stroke of the generator, since overtravel will not in any sense impair the efficiency of function of the mechanism.

It is a further object of the invention to provide an impulse generator of the general class noted above, wherein the individual parts are of simple form and designed in opposite identical pairs, so that the units may be manufactured and assembled with unusual production economies, yet will provide a smooth operating, rugged and trouble free assembly.

A present preferred embodiment of the invention is illustrated in the drawings herein, wherein:

Figure 1 is a plan view of an impulse generator according to the present teachings;

Figure 2 is an end elevational view thereof;

2

Figure 3 is a central sectional view taken on the plane of the line 3—3 of Figure 1; and

Figure 4 is a central sectional view similar to Figure 3, but showing the armature of the unit in changed position.

The essential parts of the generator include an electromagnetic winding, with an armature and field shiftable with respect to each other to cause a rapid flux change in the winding. As shown, the parts forming the field act as the frame of the unit, and consist of two identical soft iron face plates spaced apart and bolted to a pair of permanent magnets. The plates 10 and 11 are of generally rectangular shape, having flat central portions 12 and 13 terminating in opposite pairs of flat end portions 14, 15, 16 and 17 (Figure 2). The end portions 14 and 15 are spaced apart by a rectangular permanent magnet 18, which is preferably a slug of magnetic alloy such as "Alnico V," while the portions 16 and 17 are spaced apart by a magnet 19 of the same size, shape and material. The magnets 18 and 19 are both oriented in the same direction, as by having their north poles 18N and 19N in contact with the plate 10 (Figure 2), and their south poles 18S and 19S in contact with the plate 11. Thus, the plates 10 and 11 will be of opposite polarity to each other. Prior to assembly, a coil 20 is positioned between the field plates and between the magnets. The central portions 12 and 13 of the field plates 10 and 11 are slotted, as indicated at 21 and 22, and the metal between these slots if bent inwardly at a right angle, provides a magnetic pole at each side of each of the plates. The poles 23N and 24N overhang the end of the winding 21, and since both of these poles are part of the plate 10, they are both of the same magnetic polarity. That is, if we assume the permanent magnets 18 and 19 to be oriented as above stated, it will be seen that the poles 23N and 24N are both of north polarity, while the poles 25S and 26S integral with the plate 11 will both be of south polarity. Thus, the poles 23N and 25S form a pair at one end of the aperture of the winding 20, while the poles 24N and 26S form a pair at the opposite end. The field plates 10 and 11 are bolted together as by cap screws 27, 28, 29 and 30, to hold the inner faces of the plates in firm surface contact with the pole surfaces of the magnets, and to hold the entire unit in assembled relation. Thus, the inwardly extending poles 23N, 24N, 25S and 26S retain the electromagnetic winding 20 in position, and each pair of these poles is held in oppositely oriented, face-to-face relation, but spaced apart from each other a distance which

is sufficient to provide a sliding fit for an armature extending through the aperture of the coil.

The armature, generally designated as 31, is of smooth, regular rectangular shape on its exterior surfaces, but is of composite internal construction, including a soft iron core consisting of two end portions 32 and 33 in alignment with each other, diagonal portions 34 and 35, and an intermediate portion 36 offset from the end portions in a lateral direction. A non-magnetic filler 38 is provided on one side of the offset central portion. Similar fillers 39 and 40 are provided on the other side of the end portions, so that the exterior surface of the armature presents substantially straight, uninterrupted slide bearing surfaces abutting the pole faces on each side. Thus, the armature has, on the left side as seen in Figures 3 and 4, a face surface 41 at one end, a face surface 42 lying in the same plane at the opposite end, and a bearing surface 43 between them and in the same plane. Similarly, the offset portion 36 has a relatively longer face surface 44—45 extending almost the full distance between the poles 25S and 26S, with contiguous surfaces 46 and 47 formed on the fillers 39 and 40. These surfaces 44, 45, 46 and 47 are parallel with the surfaces 41, 42 and 43, but are spaced apart therefrom sufficiently that the armature face 44—45 will slide against the poles 25S and 26S as the faces 41 and 42 slide into face-to-face contact with the poles 23N and 24N.

The material employed for the fillers 38, 39 and 40 may be of any suitable nonmagnetic material, such as one of the well known nonferrous, powdered metal materials ordinarily employed in so-called "oil-less" bearings. This material, common in the mechanical arts, actually consists of a nonferrous metal powder, pressed to shape and sintered, and oil impregnated. Thus, in the present case, it allows friction-free movement of the plunger within the winding and has the nonmagnetic property required.

The mechanism is operated by moving the plunger 31 in a quick, abrupt movement from the position illustrated in Figure 3 to that of Figure 4, or vice versa, and the manner in which this movement produces the impulse may be seen by comparing these two figures. It will be noted that with the parts in the position of Figure 3, the poles 23N and 26S do not contact the magnetically permeable core of the armature. Thus, the only flux path through the winding 20 extends from the pole 24N through the face 42 of the armature, thence through the diagonal portion 34 and offset portion 36 of the core, to face 45 of the core, and thence to the field pole 25S. If we assume a flux flowing from north to south, it follows that the flux direction with the parts in this position is upward as indicated by the arrow of Figure 3. When the plunger is drawn abruptly downwardly from the position of Figure 3 to the position of Figure 4, the surfaces 42 and 45 of the armature core are disengaged from the poles 24N and 25S, but the face surface 41 of the armature core engages the pole 23N of the field, while the face 44 of the armature engages the pole 26S of the field. This causes an instantaneous reversal of the flux within the winding 20, since the flux path is now downwardly through the armature. The quick reversal of the flux within the winding 20 thus generates a momentary high potential in response to quick longitudinal movement of the plunger in either direction.

It is to be noted, however, that the coacting poles of the field and faces of the armature, through

which the magnetic circuit through the winding is reversed, slide smoothly across each other rather than striking each other in the hammer-like action characteristic of prior impulse generators. The result is that the noise and inevitable wear incident to the hammering of prior devices is avoided, yet an instant high potential is developed. In addition, the present design allows for any required overtravel, so that the parts of the unit need not be precisely adjusted to correspond to the stroke of its driving mechanism, yet the parts cannot be damaged if the stroke of the driving mechanism exceeds the required stroke of the generator.

Having thus described my invention, what I claim as new and desire to secure by United States Letters Patent is:

1. In an impulse generator, the combination, with an electromagnetic winding having a core aperture therein, of a pair of soft iron field plates, with the opposite plates of said pair positioned on opposite sides of the winding, and at least one permanent magnet extending between said field plates whereby the field plates are of opposite polarity; each of said field plates having two pole portions of like polarity, with one of said pole portions extending inwardly toward the core aperture at one end of the winding, and the second pole portion extending inwardly toward the aperture at the opposite end of the winding; the two pole portions of each field plate lying in the same plane so that the unlike pairs of poles of the opposite field plates are positioned in oppositely oriented face-to-face relation on opposite sides of both ends of the core aperture; together with a flux reversing armature comprising a plunger extending through the aperture of the winding and slidable therein, said plunger having a magnetically permeable core including aligned end portions having two face surfaces lying in the same plane and in sliding engagement of the two like poles of one of the field plates, an offset intermediate portion including face surfaces in sliding engagement with the two like poles of the opposite field plate, and nonmagnetic filler portions having bearing surfaces contiguous with said face surfaces.

2. In an impulse generator, the combination, with an electromagnetic winding having a core aperture therein, of a pair of soft iron field plates, with the opposite plates of said pair positioned on opposite sides of the winding, and at least one permanent magnet extending between said field plates whereby the field plates are of opposite polarity; each of said field plates having two pole portions of like polarity, with one of said pole portions extending inwardly toward the core aperture at one end of the winding, and the second pole portion extending inwardly toward the aperture at the opposite end of the winding; the two pole portions of each field plate lying in the same plane so that the unlike pairs of poles of the opposite field plates are positioned in oppositely oriented face-to-face relation on opposite sides of both ends of the core aperture; together with a flux reversing armature comprising a plunger extending through the aperture of the winding and slidable therein, said plunger having a magnetically permeable core including aligned end portions having two face surfaces lying in the same plane and in sliding engagement of the two like poles of one of the field plates, and an offset intermediate portion including face surfaces in sliding engagement with the two like poles of the opposite field plate.

3. In an impulse generator, the combination, with an electromagnetic winding having a core aperture therein, of a pair of soft iron field plates, with the opposite plates of said pair positioned on opposite sides of the winding, and at least one permanent magnet extending between said field plates whereby the field plates are of opposite polarity; each of said field plates having two pole portions of like polarity, with one of said pole portions extending inwardly toward the core aperture at one end of the winding, and the second pole portion extending inwardly toward the aperture at the opposite end of the winding; the two pole portions of each field plate lying in the same plane so that the unlike pairs of poles of the opposite field plates are positioned in oppositely oriented face-to-face relation on opposite sides of both ends of the core aperture, together with a flux reversing armature comprising a plunger extending through the aperture of the winding and slidably therein; said plunger having face surfaces on the opposite sides thereof in sliding engagement with the two pairs of magnetic poles of the field plates, and at least one magnetically permeable core portion extending diagonally between said opposite face surfaces; together with nonmagnetic filler portions having bearing surfaces contiguous with said face surfaces and in sliding engagement with the poles of the field plates.

4. In an impulse generator, the combination, with an electromagnetic winding having a core aperture therein, of a pair of soft iron field plates, with the opposite plates of said pair positioned on opposite sides of the winding, and at least one permanent magnet extending between said field plates whereby the field plates are of opposite polarity; each of said field plates having two pole portions of like polarity, with one of said pole portions extending inwardly toward the core aperture at one end of the winding, and the second pole portion extending inwardly toward the aperture at the opposite end of the winding; the two pole portions of each field plate lying in the same plane so that the unlike pairs of poles of the opposite field plates are positioned in oppositely oriented face-to-face relation on opposite sides of both ends of the core aperture, together with a flux reversing armature comprising a plunger extending through the aperture of the winding and slidably therein; said plunger having face surfaces on the opposite sides thereof in sliding engagement with the two pairs of magnetic poles of the field plates, and at least one magnetically permeable core portion extending diagonally between said opposite face surfaces.

5. In an impulse generator, the combination, with an electromagnetic winding having a core aperture therein, of a magnetic field comprising at least one permanent magnet and a plurality of field plates; said field plates having two pairs of poles, with one pair of poles adjacent the core aperture at one end of the winding, and the second pair of poles adjacent the aperture at the opposite end of the winding; together with a flux reversing armature comprising a plunger extending through the aperture of the winding and slidably therein; said plunger having a magnetically permeable core including two aligned end portions having face surfaces in sliding engagement with two poles of like polarity, and an intermediate portion including face surfaces in sliding engagement with the other two poles of the field.

6. In an impulse generator, the combination, with an electromagnetic winding having a core

aperture therein, of a pair of soft iron field plates, with the opposite plates of said pair positioned on opposite sides of the winding, and at least one permanent magnet extending between said field plates whereby the field plates are of opposite polarity; each of said field plates having two pole portions of like polarity, with one of said pole portions extending inwardly toward the core aperture at one end of the winding, and the second pole portion extending inwardly toward the aperture at the opposite end of the winding; the two pole portions of each field plate lying in the same plane so that the unlike pairs of poles of the opposite field plates are positioned in oppositely oriented face-to-face relation on opposite sides of both ends of the core aperture; together with a flux reversing armature comprising a longitudinally sliding plunger extending across both pairs of said poles, said armature including guiding means and a magnetically permeable core with an offset portion therein; the core having two face surfaces in the same plane and spaced apart from each other to slide across one pole of each of the pairs of field poles, and intermediate face surfaces on the offset portion of said core to slide against the opposite pole of either of the pairs of field poles.

7. In an impulse generator, the combination, with an electromagnetic winding having a core aperture therein, of a pair of soft iron field plates, with the opposite plates of said pair positioned on opposite sides of the winding, and at least one permanent magnet extending between said field plates whereby the field plates are of opposite polarity; each of said field plates having two pole portions of like polarity, with one of said pole portions extending inwardly toward the core aperture at one end of the winding, and the second pole portion extending inwardly toward the aperture at the opposite end of the winding; the two pole portions of each field plate lying in the same plane so that the unlike pairs of poles of the opposite field plates are positioned in oppositely oriented face-to-face relation on opposite sides of both ends of the core aperture; together with a flux reversing armature comprising a plunger extending across both pairs of said poles, said armature being of composite formation consisting of nonmagnetic portions having smooth bearing surfaces thereon, and a magnetically permeable core having an offset portion and a portion extending diagonally with respect to said bearing surfaces and having a plurality of face surfaces spaced apart from each other and adapted to slide across the surfaces of both of the pairs of field poles; the face surfaces of the core being contiguous with the aforementioned bearing surfaces to provide substantially continuous guide surfaces for the plunger.

8. In an impulse generator having a field comprising two pairs of magnetic poles spaced apart from each other, the combination of an armature comprising a sliding plunger extending across both pairs of said poles, said armature being of composite formation consisting of nonmagnetic portions having smooth bearing surfaces thereon, and a magnetically permeable core having an offset portion and a portion extending diagonally with respect to said bearing surfaces and having a plurality of face surfaces spaced apart from each other and adapted to slide across the surfaces of both of the pairs of field poles; the face surfaces of the core being contiguous with the aforementioned bearing surfaces to provide sub-

stantially continuous guide surfaces for the plunger.

9. In an impulse generator having a field comprising two pairs of magnetic poles spaced apart from each other, the combination of an armature comprising a longitudinally sliding plunger extending across both pairs of said poles, said armature including guiding means and a magnetically permeable core with an offset portion therein; the core having two face surfaces in the same plane and spaced apart from each other to slide across one pole of each of the pairs of field poles, and intermediate face surfaces on the offset portion of said core to slide against the opposite pole of either of the pairs of field poles.

10. In an impulse generator, a flux reversing armature comprising a magnetically permeable core having two opposite end portions aligned with each other and having face surfaces lying in the same plane and disposed on the same side of the core; and an offset intermediate portion between the end portions and having face surfaces disposed on the opposite side of the core from the face surfaces of the end portions; together with nonmagnetic filler portions having bearing surfaces contiguous with said face surfaces to provide substantially continuous guide surfaces for the armature.

11. In an impulse generator, a field compris-

ing two pairs of magnetic poles spaced apart from each other, an armature comprising a longitudinally sliding plunger extending across both pairs of said poles and including a magnetically permeable core having two opposite end portions aligned with each other and having face surfaces lying in the same plane and disposed on the same side of the core to slide across one pole of each of said pairs, and an offset intermediate portion between the end portions and having face surfaces disposed on the opposite side of the core from the face surfaces of the end portions, to slide against the opposite pole of either of said pairs, and guiding means operatively associated with said poles and said armature for supporting it in sliding relationship to said poles.
